Patented Nov. 3, 1914.

UNITED STATES PATENT OFFICE.

JOHN W. WHITCHER, OF BOSTON, MASSACHUSETTS.

BELT-CLAMP.

1,115,993.

Specification of Letters Patent.

Patented Nov. 3, 1914.

Application filed August 8, 1911. Serial No. 643,022.

To all whom it may concern:

Be it known that I, JOHN W. WHITCHER, a citizen of the United States, residing at Boston, in the county of Suffolk and State 5 of Massachusetts, have invented certain new and useful Improvements in Belt-Clamps, of which the following is a specification.

This invention relates to belt clamps.

The object of the invention is to improve 10 generally the construction of belt clamps so that the clamps may easily be applied to belts to tighten the same and so that the clamps may be easily and quickly removed from the belts without detaching the nuts 15 from the various bolts and screw-rods, and without the necessity of employing the services of more than one man in the application of the clamps or the removal thereof from the belt.

20 With the above and other objects in view the present invention consists in the combination and arrangement of parts hereinabove more fully described, illustrated in the accompanying drawings and particularly 25 pointed out in the appended claims, it being understood that changes may be made in the form, proportion, size and minor details without departing from the spirit or sacrificing any of the advantages of the invention.

30 In the drawings:—Figure 1 is a top plan view illustrating the application of my invention. Fig. 1^a is a detail plan view of a portion of the clamp shown in Fig. 1. Fig. 35 2 is a side view of one of the clamps with the belt removed therefrom. Fig. 3 is a side view of one of the clamps partly in section illustrating the position of the clamping members in dotted lines when it is 40 desired to apply the clamp to the belt or to remove it therefrom. Fig. 4 is a view of a modified form of clamp partly in side view and partly in section.

45 Referring now more particularly to the accompanying drawings the reference character 1 indicates a belt whose ends are connected together by lacing or otherwise as indicated at 2, the belt being held between clamps A and B, each clamp A and B, as 50 shown in Figs. 1 to 3, inclusive, being the same in construction, thereby necessitating

a description of but one clamp which will now be described.

The characters 3 and 4 indicate upper and lower clamping members, respectively, each 55 having its inner face notched to provide end slots *a* and *b* for a purpose presently explained, these slots *a* and *b* being arranged horizontally with reference to the clamp, the slot *a* intersecting a vertical slot *c* 60 formed by bifurcating one end of each of the clamping members 3 and 4.

The character 5 indicates a pin passed transversely through one end of the lower clamping member 4 and through the slot *c* 65 and on which pin 5 the eye-bolt 6 is secured and whereby the eye-bolt may be swung into and out of the vertical slot *c*, there being a nut and washer 7 and 8, respectively, secured on the outer end of the eye-bolt 6 for 70 the purpose of holding the eye-bolt in such position with reference to the clamping members 3 and 4 as to provide for an efficient clamping of the belt 1 between the clamping members.

75 Secured to the under face of the lower clamping member 4 is a metallic or other plate 9 provided with a rectangular opening adapted to align with the openings 10 and 11 of the clamping members 3 and 4 80 and through which opening is passed the bolt 12 whose shank adjacent its head 13 is squared as indicated at 14 to fit in the square opening of the plate 9 to prevent turning of the bolt 12, there being a nut 85 and washer 15 and 16, respectively, secured to the bolt 12 to insure clamping of this particular end of the clamp on the belt.

85 Secured to the outer side faces of the clamping members 3 and 4 at each end 90 thereof is a plate 17 provided with a lug 18, there thus being a pair of plates 17 carried by each clamping member and it will be seen that the lugs 18 of opposing plates of coöperating clamping members are ar- 95 ranged preferably in alinement for the purpose of preventing turning of the nuts 19 carried by the screw rods 20 and 21 which latter are fitted in the aforesaid horizontal slots *a* and *b*, respectively. The screw-rods 100 20 and 21 are preferably made in one piece, provided with right and left screw-threads

and nuts upon opposite ends and an enlarged portion d , intermediate the ends to provide means to turn said rods. It is obvious that each of said rods might be made in two parts with their threaded ends connected with a turn-buckle in the center in the usual manner, if so desired. By virtue of the nuts 19 at the ends of these screw rods 20 and 21 engaging the lugs 18 of the plates 17 the nuts cannot turn and therefore it is unnecessary to have two men manipulate the clamp when tightening the belt, that is, one man for operating the screw rods by the enlarged portion d and another man or men to prevent turning of the nuts 19.

When it is desired to remove the clamps from the belt it is simply necessary to slightly slacken the nut 7 on the bolt 6, when the clamps will loosen on the belt and the screw-rods 20 and 21 are thereby freed from any strain and may be readily removed intact. It is then only necessary to a little farther unscrew the nut 7 on the bolt 6 when the latter may be thrown out to the dotted line position indicated in Fig. 3 and the upper clamp 3 elevated as shown in dotted lines in Fig. 3 when the clamp may be moved laterally away from the belt, thereby obviating the necessity of completely swinging the clamping member 3 around from over the clamping member 4 on the bolt 12. It will be seen that the openings 10 and 11 of the clamping members are elongated with their greater diameters extending longitudinally of the clamping members, said elongated openings having their greater diameters increasing in length throughout the thickness of the clamping members. This is done to give the bolt 12 considerable play to allow the two parts of the clamp to be opened as indicated in dotted lines in Fig. 3 so as to readily apply the clamp to the belt or permit removal of the clamp from the belt, the clamping members 3 and 4, in other words, having not only movement away from each other at one end but also, by virtue of the elongated openings 10 and 11, having slight longitudinal movement upon each other so as to insure ready application of the belt by the clamping members or removal of the clamping members from the belt.

In Fig. 4 there is shown a little different type of clamping member wherein the clamping members 3' and 4' are each notched at each end to provide the horizontal slots a' and b' corresponding to the slots a and b of the preferred form of the invention. The clamping members 3' and 4' are also provided with openings 10' and 11', respectively. The openings 10' and 11' are elongated similar to the openings 10 and 11 of Figs. 1, 2 and 3, but the opening 11'

has its smallest diameter equal to the largest diameter of the opening 10' so that when the clamping members 3' and 4' are superimposed the openings 10' and 11' align so that an opening is formed which increases in size from the top of member 3' down through the bottom of member 4', as clearly shown in Fig. 4. Through the openings 11' of the lower clamping member 4' is passed a pin 5' on which the hook bolts 22 are secured, there being nuts 23 and washers 24 disposed on the hook bolts 22 to insure a binding engagement of the clamping members 3' and 4' on the belt.

While the last form described is not the preferred one, it is one that is very convenient and easily operated.

What is claimed is:—

1. A belt clamp comprising clamping members each provided with vertical openings, said openings being elongated with their greater diameters extending longitudinally of the clamping members and said openings having their greater diameters increasing in length throughout the thickness of the clamping members, said openings having one end of each in mutual alinement. 85

2. A belt clamp comprising clamping members each provided with vertical openings, extending through the clamping members, said openings being elongated and increasing in size from one surface of the clamping member toward the opposite surface, with the greater diameters disposed longitudinally of the clamping members, said openings having one end of each in mutual alinement. 95

3. A belt clamp comprising two superimposed clamping members provided with vertical openings disposed near one end of each member but spaced therefrom, said openings being elongated and increasing in size from one surface of the clamping members toward the opposite surface with the greater diameters disposed longitudinally of the clamping members, bolts slidably mounted within the openings of the clamping members, the inner wall of each of said openings being straight and substantially perpendicular to the body of the clamping members with the opposite wall inclining downwardly and outwardly to permit movement of the free end of the clamping members relative to the other when the bolts are loosened. 110

4. A belt clamp comprising two superimposed clamping members detachably secured together at one end each having a vertical opening at its other end, a bolt passing through the openings in the clamping members, and means to secure the bolt in said openings, said openings being spaced from the ends of the clamping members and having their inner walls straight and in 125

vertical alinement with each other, with their outer walls inclining downwardly and outwardly from the upper surface of each clamping member toward the lower surface to provide an elongated opening increasing in length throughout the thickness of the clamping members whereby the free end of the upper clamping member may be ele-

vated without withdrawing the bolt at its other end.

In testimony whereof I affix my signature in presence of two witnesses.

JOHN W. WHITCHER.
